UNITED STATES PATENT OFFICE.

GEORGE FREDERICK BULL, OF BIRMINGHAM, ENGLAND.

CARBURETER FOR INTERNAL-COMBUSTION ENGINES.

1,116,986.

Specification of Letters Patent. Patented Nov. 10, 1914.

Application filed March 25, 1912. Serial No. 685,990.

To all whom it may concern:

Be it known that I, GEORGE FREDERICK BULL, a subject of the King of Great Britain, residing at Birmingham, England, have 5 invented certain new and useful Improvements in Carbureters for Internal-Combustion Engines, of which the following is a specification.

This invention relates to carbureters for 10 internal combustion engines principally of that type in which the fuel is sprayed and atomized by a current of air which is drawn, by the suction of the engine, past the fuel nozzle, the proper explosive mixture being 15 produced by means of an independent supply of air, also drawn in by the suction of the engine, which meets and mixes with the said spray.

The principal object of the present invention 20 is to provide an improved construction of this type of carbureter in which a more thorough atomizing of the fuel is insured, and a more perfect and intimate mixture of the main air supply with the sprayed fuel 25 obtained, thus producing a more perfect explosive charge.

Figure 1 of the accompanying drawings is a side elevation of a carbureter constructed in accordance with this invention. Fig. 2 is a longitudinal vertical section through 30 the carbureter, the float-feed chamber being shown in elevation. Fig. 3 is a horizontal section. Fig. 4 is a cross-section on line α^1 , Fig. 2, Fig. 5 is a section on line α^1 , Fig. 2, 35 showing the air regulator. Fig. 6 is a section on line α^2 , Fig. 2. Fig. 7 is a view showing the float-feed chamber and fuel nozzle detached from the body of the carbureter. Fig. 8 is a section on line α^3 Fig. 2. 40 The same reference numerals indicate corresponding parts in each of the figures of the drawings.

The body of the carbureter comprises an outer cylindrical shell or casing 1 contracted 45 at one end, which is adapted to be connected with the induction pipe of the engine by a union 2, and is somewhat enlarged at its opposite end, at 3. It is fitted within its interior with a removable liner or sleeve 4, 50 of smaller diameter, having an enlarged coned rear end 5. This said end is fitted with a transverse diaphragm 6 formed with a series of air-inlet openings 7 leading into a chamber 8 formed by the enlarged part 3 55 of the casing 1, the walls of the chamber being provided with a number of peripheral

openings 9 leading to the exterior and through which is drawn the air supply for diluting and forming the mixture. This diluting supply is controlled by a rotating 60 regulator consisting of a disk 10 mounted behind the transverse diaphragm 6 upon a central sleeve or hollow boss 11 carried by the latter, and having a number of openings 12 adapted to be brought more or less into 65 register with those of the said diaphragm. It is preferably operated by a suitable transmission device actuated by a lever from the handle-bar (in the case of a motor-cycle) or other part. In the construction illustrated, one side of the casing 1 carries a vertical tubular housing 13 (shown in section in Fig. 6) to whose upper end the outer stationary element or casing 14 of the transmission device may be attached by a screw 75 cap 15. The inner wire element 16 is attached to an externally threaded part 51 screwing into a hollow plunger 17 having a forked lower-end contained within a loose sleeve 34 fitted in the housing 13, and having 80 a transverse pin 18 crossing the forked part. By screwing the part 51 more or less into the plunger the length of the cable can be adjusted. The pin 18 engages with a slotted end of an arm 19 carried by the air regulator 10, and which extends through a slot 20 in the sleeve 34. The plunger is surrounded by a spring 21 which tends to depress the same so as to close the air inlets. By operating the control lever (not shown) the 90 plunger is raised and lowered so as to more or less open and close the air inlets.

The rear of the air-inlet chamber 8 is closed by a cone 22 loosely fitting within the open end of the casing 1 and provided with 95 a nozzle 23 which extends horizontally through the air-inlet chamber and projects into the main part of the body which forms the mixing chamber, said nozzle (which has a small orifice) being supported by the central sleeve 11 carried by the air-inlet diaphragm 6. Through this cone 22 the air for spraying the fuel is drawn by the suction of the engine, said cone being provided adjacent its outlet end with an internal annular constriction 39 which serves to produce 100 an increased velocity at that point.

The rear part of the body carries a set-down bracket 24 which supports the float-feed chamber 25 and is provided with vertical curved side walls 26, which embrace and fit around the front portion of said chamber.

There is thus formed between the latter and the cone 22 a chamber 27 (Fig. 3) which communicates with the exterior through openings 28 in the sides, forming an area of undisturbed air from which the air for forming the spray is drawn. The float chamber 25 is detachably secured to the carrier bracket 24, for which purpose the latter is longitudinally slotted at 29 to receive the supply branch 30 at the bottom, said branch 30 being fitted with a nut 31 by the screwing up of which the chamber can be rigidly secured in position. The said chamber 25 carries at its lower end a forwardly extending bracket piece or block 32 which passes through an opening 33 in the vertical wall 26 of the bracket 21, and extends horizontally beneath the carburetor body. It is drilled with a horizontal fuel passage 35 which terminates in a vertical hole 36 into which a vertical petrol nozzle 37 is screwed, said passage registering with a corresponding passage 38 in the nozzle. The lower end of the latter is coned to engage with an internally coned part of the hole 36. The said nozzle passes into the interior of the mixing chamber and its upper end is coned and fits within a conical recess in the underside of the air nozzle 23 at the point where the construction 39 is provided, so as to extend into the bore of the said air nozzle at right angles thereto. By removing the fuel nozzle and slackening the fixing nut 31 of the supply branch 30 the float chamber 25 can be slid rearward away from the body, as in Fig. 7. The suction of the engine causes a strong current of air to be drawn through the openings 28 and the cone 22 and across the petrol jet 37, thereby inducing a flow of petrol which is immediately atomized and sprayed by the said air. At the same time the suction draws the diluting supply of air through openings 9 into the inlet chamber 8 and past the regulator, whence it enters the mixing chamber co-axially or concentrically with the spraying air jet issuing through the nozzle 23 and intimately mixes with the spray for forming the explosive mixture.

The throttle valve 40 is of the butterfly type and is operated by a transmission device in a similar manner to the air regulator, previously described. Thus, the casing 1 has a tubular housing 41 containing a sleeve 42 (Fig. 8), and having attached to its upper end, by means of a screw-cap 43, the outer member 44 of the transmission device. The inner wire member 45 is attached to a plunger 46 surrounded by a spring 47 and having a forked lower end 48 provided with a pin 49 engaging with the slotted end of an arm 50 fixed upon the axis of the valve 40. The wire 45 is operated by a suitable control lever so as to vary the amount of opening of the valve according to requirements.

Having fully described my invention,

what I desire to claim and secure by Letters Patent is:—

1. A carburetor of the type herein referred to, comprising a horizontal body part, a float-feed chamber carried by one end of the body, an air-inlet cone fitted in said end and having a horizontal nozzle through which air is drawn by the suction of the engine, solely for spraying the fuel, a chamber between said float chamber and the air-inlet cone provided with inlet openings in its side walls, and a vertical fuel nozzle arranged at right angles to the nozzle of said air-inlet cone so that the fuel is sprayed by the air issuing from the latter, the peripheral wall of the rear end of the carburetor body having air-inlet openings through which the diluting air supply is drawn by the suction of the engine concentrically with the first-named nozzle for mixing with the sprayed fuel and forming the proper explosive charge, substantially as herein described and set forth.

2. A carburetor comprising a horizontal body part, a vertical fuel nozzle extending into the interior of the body, a transverse perforated diaphragm at the rear end of the body, a rotary air regulator disk arranged against the face of the diaphragm and having openings adapted to be turned more or less into register with the openings in the diaphragm, an air-inlet cone provided with a horizontal nozzle through which air is drawn by the suction of the engine, said nozzle passing through and being supported by said diaphragm, and an air-inlet chamber located between the air regulator and the funnel, and provided with openings through which a diluting air supply is drawn by the suction of the engine.

3. A carburetor comprising a horizontal body, a set-down bracket at one end thereof provided with a longitudinal slot, a float-feed chamber detachably supported by said bracket, curved side walls carried by the bracket which partially embrace the front portion of the float-feed chamber, a supply branch at the bottom of said chamber received in said slot to admit of the chamber being detached by sliding it rearward, and a nut on the supply branch for securing the said chamber in position.

4. A carburetor comprising a horizontal body, a set down bracket at the rear end thereof having a longitudinal slot and an opening, a float-feed chamber detachably supported by said bracket, curved side walls carried by the bracket which partially embrace the front portion of the float-feed chamber, a supply branch at the bottom of said chamber received in the slot in said bracket, a nut on the supply branch for securing the said chamber in position, an air-inlet cone fitted in the rear end of the body

- and having a horizontal nozzle through which air is drawn by the suction of the engine solely for spraying the fuel, a chamber between the float chamber and the cone 5 having inlet openings in its side walls, a forwardly extending block carried by the float chamber and passing through the opening in said bracket, and having a longitudinal fuel passage, and a vertically arranged det- 10 tachable fuel nozzle carried by said block and extending into the body at right angles to the air nozzle so that the fuel is sprayed by the air issuing from the latter, the peripheral wall of the rear end of the carbureter body having air-inlet openings 15 through which the diluting air supply is drawn by the suction of the engine concentrically with the central spraying nozzle for mixing with the sprayed fuel and forming the proper explosive charge.
5. A carbureter comprising a horizontal body part, a vertical fuel nozzle extending into the interior of the body, an air inlet funnel at one end of the body, and a central 20 horizontal spraying nozzle of small bore carried by said funnel and through which a current of air used solely for spraying the fuel is drawn by the suction of the engine, said spraying nozzle being arranged above and at right angles to the fuel nozzle and having its forward portion provided with an internal annular constriction which is formed at the under side thereof with a recess opening into its bore and receiving 25 therein the upper end of said fuel nozzle to produce an increased velocity adjacent to the said upper end of said fuel nozzle, the carbureter body having air-inlet openings through which the diluting air supply is drawn by the suction of the engine to mix 40 with the sprayed fuel and form the proper explosive charge.
6. A carbureter comprising a body part, a fuel nozzle extending into the interior of the body and having a coned outer end, an air inlet funnel at one end of the body, and a spraying nozzle carried by said funnel and through which a current of air used solely for spraying the fuel is drawn by the suction of the engine, said spraying nozzle 45 extending at one end across and beyond the coned end of said fuel nozzle and having its bore formed adjacent said end with an annular constriction, the under side of the spraying nozzle being formed with a conical 50 seat which opens into said constriction and receives the coned end of the fuel nozzle, to produce an increased velocity adjacent to the said coned end of said fuel nozzle, one wall of said carbureter body being provided 55 with air-inlet openings through which the diluting air supply is drawn by the suction of the engine to mix with the sprayed fuel and form the proper explosive charge.
- In testimony whereof I have hereunto set my hand in presence of two subscribing witnesses.

GEORGE FREDERICK BULL.
